ADJUSTABLE BED

Marie Lindquist, San Francisco, Calif.

Application October 23, 1947, Serial No. 781,607

5 Claims. (Cl. 5—63)

1

This invention relates to improvements in adjustable beds.

An object of my invention is to provide an adjustable bed having novel means for raising and lowering either or both of its ends.

Another object of my invention is to provide a novel bed adapted for hospital and other uses, embodying hand operated means by which either the foot or head ends of the bed may be raised or lowered or the supporting frame of the bed may be vertically adjusted to position the occupant at a desired height above the floor level.

Other and further objects of my invention will be pointed out hereinafter, indicated in the appended claims, or will be obvious to one skilled in the art upon an understanding of the present disclosure. For the purpose of this application I have elected to show herein certain forms and details of an adjustable bed representative of my invention; it is to be understood, however, that the embodiment of my invention herein shown and described is for the purpose of illustration only and is not to be regarded as limiting the scope of the invention in the art.

In the accompanying drawings:

Fig. 1 is a side elevation of an adjustable bed embodying the principles of my invention, showing by the broken lines the supporting frame in a raised position;

Fig. 2 is an end view of the bed;

Fig. 3 is a side view of the bed showing the head end thereof in a raised position;

Fig. 4 is a similar view showing the foot end of the bed in a raised position;

Fig. 5 is an enlarged sectional view taken on the line 5—5 of Fig. 4; and

Fig. 6 is a diagrammatic plan view of the means employed in adjusting the bed to different positions.

The frame of the bed which ordinarily supports the springs and mattress embodies a head portion 1, a foot portion 2 and an intermediate connecting portion 3. Both of the head and foot portions 1 and 2 have depending tubular legs 4 which are aligned with upwardly extending tubular posts 5.

The means for vertically adjusting the frame as a whole or either of the head or foot portions 1 and 2 with respect to the other embodies a mechanism which is preferably housed within the tubular members of the bed frame.

Positioned in each leg 5 is a non-rotatable supporting shaft which has an upper threaded portion 6 and a lower squared or otherwise suitably shaped portion 6', the latter having a caster 7

2

mounted thereon. The lower portion 6' of each shaft extends through a fixed collar 8 which prevents the rotation of the shaft. Operatively engaging with the threaded portion 6 of each shaft is a nut 9 which carries a bevel gear 10, the said nut having an annular groove 11 therein into which a pin or screw 12 secured to a leg 4 extends. The screws 12 are secured to the legs 4 and they permit the rotation of the nuts 9 but not the up or down movement thereof with respect to the legs. Engaging with each bevel gear 10 is a similar gear 13 which is connected by an inwardly disposed horizontal connecting rod 14 to a bevel gear 15. Each connecting rod 14 is rotatably mounted in bearings 16 supported on the frame.

The bevel gears 15 associated with the head portion of the bed frame are arranged for operative engagement with a similar bevel gear 17 secured to the forward end of a shiftable and rotatable operating shaft 18 which is supported in bearings 19 carried on the bed frame. The operating shaft 18 extends rearwardly through a housing 20 supported centrally on the foot portion 2 of the bed frame, and a hand crank 21 secured to the rear end of the operating shaft provides means for rotating it in either direction. Secured to the rear end portion of the operating shaft 18 are suitably spaced bevel gears 22 and 23, either of which is adapted to engage with the bevel gears 15 associated with the foot portion 2 of the bed frame, depending on the particular position of the operating shaft 18. The bevel gear 17 is connected by a suitable spline arrangement to the forward end of the operating shaft 18, thereby making it possible for the said gear to slide forwardly or rearwardly on the said shaft and at the same time rotate therewith. A helical compression spring 24 engaging with the enlarged end of the bevel gear 17 urges the latter forwardly. It will be noted by observing the relative positions of the gears in Fig. 6 that when the bevel gear 23 is in engagement with the two gears 15 associated with the foot portion 2 of the bed frame, the gear 17 is disconnected from the gears 15 associated with the head portion 1 of the bed frame, and vice versa. Thus when the gear 23 is meshed with its associated gears 15 the foot portion 2 of the bed frame may be raised or lowered by turning the crank 21, and when the gear 17 is meshed with its associated gears 15 the head portion 1 of the bed frame may be vertically adjusted. To permit both ends of the bed frame to be simultaneously raised or lowered the gear 22 must be in engagement with the gears

15 associated with the foot portion 2 of the bed frame at the same time the gear 17 is connected to its associated gears. The gears 17 and 22 are so arranged that the latter does not engage with its associated gears 15 until the shaft 18 has been progressively shifted in a rearward direction sufficiently to first bring the gear 22 into engagement with its associated gears 15 and then to a further extent (permitted by the contraction of the compression spring 24) to effect the engagement of the gear 22 with the rearwardly disposed gears 15. Thus when both of the gears 17 and 22 are respectively meshed with their associated gears 15, the bed frame as a unit may be vertically adjusted by turning the operating shaft 18.

The means employed for shifting the operating shaft 18 includes the following mechanism. The housing 20 is internally threaded to permit a spirally grooved cam member 25 to operatively engage therewith. The cam member 25 has a handle 26 on its outer end and its inner end is formed with an annular groove 27 within which is rotatably confined an annular flange 28 secured to the operating shaft 18. By turning the handle 26 in a certain direction the cam member 25 is moved forwardly, thereby shifting the operating shaft in the same direction and thus effecting the engagement of the gear 23 with its associated gears 15. By turning the cam member in the opposite direction to a predetermined extent the operating shaft 18 is shifted rearwardly to effect the connection of the gear 17 with its associated gears 15, and when the cam member is further turned in this same direction the shaft is shifted still farther to the rear to also effect the engagement of the gear 22 with its associated gears 15. It will be noted that the threaded portions 6 of the supporting shafts at the left hand side of the bed frame have right hand threads while those on the right hand side have left hand threads, it being necessary to have the supporting shafts at opposite sides of the bed frame oppositely threaded to permit the proper raising and lowering of the head and foot ends of the bed frame.

When the cam 25 has once been adjusted to effect the suitable shifting of the operating shaft 18 to position certain gears in operative engagement with one another, the crank 21 is turned in a direction required to effect the desired adjustment of the bed frame. As the then connected set or sets of gears 15 are rotated the nuts 9 associated with the latter are also rotated and are thereby made to move either upwardly or downwardly on the screw portions 6 of their associated supporting shafts, depending upon the particular direction the crank 21 is turned. Since the legs 4 are connected to the nuts 9 and move with them either upwardly or downwardly, the particular end or ends of the bed frame associated with the nuts then being rotated will be vertically adjusted.

What I claim is:

1. An adjustable bed comprising a supporting frame having tubular front and rear legs, a non-rotatable threaded supporting member positioned in and extending below each leg, a rotatable nut operatively engaging with each threaded supporting member, means connecting each nut with its associated leg whereby the leg may be vertically adjusted in accordance with the adjust-

ment of the nut on its associated threaded member, and means for selectively rotating the nuts of either the front legs or the rear legs or all of the nuts simultaneously.

5 2. An adjustable bed comprising a supporting frame having front and rear pairs of tubular legs, a non-rotatable threaded supporting member positioned in and extending below each leg, a rotatable nut mounted in each leg and operatively engaging with each threaded supporting member, and arranged for vertical adjustment thereon, each of the said nuts being rotatably connected with its associated leg but not longitudinally adjustable therein, whereby the leg may be vertically adjusted in accordance with the adjustment of the nut on its associated threaded member, means for selectively rotating the nuts associated with either the front or rear pair of legs or the nuts of both pair of legs simultaneously.

10 3. An adjustable bed comprising a supporting frame having front and rear pairs of tubular legs, a non-rotatable threaded supporting member positioned in and extending below each leg, a rotatable nut mounted in each leg and operatively engaging with each threaded supporting member and arranged for vertical adjustment thereon, each of the nuts being rotatably connected with its associated leg but not longitudinally adjustable therein, whereby the leg may be vertically adjusted in accordance with the vertical adjustment of the nut on its associated threaded member, a gear secured to each nut, and means for selectively rotating the gears of either pair of legs or the gears of both pairs of legs simultaneously.

15 4. An adjustable bed comprising a supporting frame having front and rear pairs of tubular legs, supporting screws mounted in and extending below the legs, rotatively adjustable nuts mounted in the legs and engaging with the supporting screws and arranged for up and down adjustment thereon, the said legs being supported from the adjustable nuts, and means for selectively adjusting the nuts associated with either the front or the rear pair of legs or both pairs of legs simultaneously.

20 5. An adjustable bed, supporting frame having front and rear pairs of tubular legs, non-rotatable externally threaded members positioned in and extending below the legs, rotatable internally threaded elements adjustably engaging with the threaded members and arranged in connected and supporting relationship with the legs, and means for simultaneously rotating the elements of either pair of legs or all of the elements simultaneously, whereby either pair of legs or all of the legs may be vertically adjusted with respect to the floor.
